1

The present invention relates to a method of and means for producing harmonics from a fundamental frequency. It is known to produce harmonics from a fundamental frequency by passing a current of fundamental frequency through a non-linear transmission means and segregating the harmonics by suitable filtering means. Such known devices require a considerable number of switching elements as well as filters.

The present invention relates to a novel method of and means for producing harmonics which differs basically from these known devices. The invention makes use of the fact that when a sufficiently high carrier frequency f_0 is modulated with a fundamental frequency f_1 , a series of side band frequencies will occur at both sides of the carrier frequency, the spacing between said side band frequencies being equal to f_1 .

According to the invention, whole number multiples are obtained from the fundamental frequency f_1 by modulating a considerably higher carrier frequency with the fundamental frequency, passing at least two of the side band frequencies thus formed and differing from each other by the fundamental frequency through a filter to an amplitude modulator, and providing at the output end of said modulator further filters which allow the desired whole number multiples of the fundamental frequency to pass. The higher carrier frequency and its undesirable side bands as well as the sum frequencies resulting from the modulation, are suppressed at the output end.

The invention will be further explained by reference to a number of constructional examples illustrated diagrammatically in the accompanying drawings, wherein:

Fig. 1 is a block diagram showing a basic system for generating harmonic frequencies according to the invention;

Figs. 2, 3 and 4 are similar block diagrams illustrating various modifications of the invention;

Fig. 5 is a block diagram illustrating the use of the invention in connection with a frequency divider;

Fig. 6 is a further block diagram illustrating the use of the invention in connection with a phase or frequency modulation system;

Figs. 7, 8 and 9 show complete and detailed circuit diagrams of harmonic-producing systems of the type according to Figs. 1, 2 and 4, respectively.

Like reference characters identify like parts in the different views of the drawings.

Fig. 1 shows a basic arrangement for produc-

ing a continuous band of harmonics from a fundamental frequency f_1 . Generator G produces an auxiliary carrier frequency f_0 of for example several megacycles. The carrier frequency is frequency-modulated with the fundamental frequency f_1 of for instance 1 kc., by applying a current or voltage of frequency f_1 to the reactance control element R. Reactance control element R and generator G together form a frequency modulator. The reactance element varies the natural frequency f_0 in rhythm with the fundamental frequency f_1 , the deviation factor or limits of frequency variation being ample, for instance about 100 kc. in the example mentioned. The reactance element R may for instance contain a known reactance tube arrangement, or it may comprise an iron core choke coil with variable inductance and premagnetised by the fundamental frequency current. Other modulating methods may also be employed. As a result, the carrier frequency f_0 and a series of side band frequencies are present at the output end of the generator G. The spacing between neighbouring side bands is equal to the fundamental frequency f_1 . A band-pass filter BP filters out a definite frequency band. The output of the band-pass filter is fed to an amplitude modulator M having a control characteristic which is essentially non-linear. Hence, combination frequencies will be formed, whereby at the output end of a subsequent low-pass filter TP, the fundamental frequency f_1 and an associated whole number of multiple frequencies can be obtained. The maximum harmonic oscillation with an adequate amplitude which can be obtained is mainly determined by the width of the band-pass filter BP and the limiting frequency of the low-pass filter TP. If for instance the frequency varies within limits considerably greater than 100 kc., and if the filter bandwidth amounts to 200 kc. and the limiting frequency of the low-pass filter is 200 kc., then about 200 frequencies with a spacing of 1 kc. can be obtained, that is frequencies from 1, 2, 3, 4, up to about 200 kc. A two-hundredfold multiplication of the fundamental frequency of 1 kc. is thus obtained.

Another arrangement according to the invention is shown in Fig. 2. The frequency modulation product which is obtained from generator G is passed over two band-pass filters BP₁ and BP₂ to the amplitude modulator M. The passing range of the filters is so selected that the filter BP₁ for instance allows the frequencies $f_0 + mf_1$ and the filter BP₂ allows the frequencies $f_0 - nf_1$ to pass, m and n being whole numbers. Beyond

the modulator and after passing through a low-pass filter TP, the following difference frequencies can be obtained:

$$(f_0 + mf_1) - (f_0 - nf_1) = (m + n)f_1$$

This is the $(m+n)$ th harmonic of the fundamental frequency f_1 . Since the carrier oscillation disappears, the special advantage of this method is that the carrier frequency does not need to be highly constant or stable. With a carrier frequency of a few megacycles and a fundamental frequency f_1 of 1 kc, the deviation or limits of frequency variation may amount to over 100 kc. Side band frequencies with $n=m=100$ then occur. There is thus a multiplication of the fundamental frequency f_1 up to a factor $n+m=200$.

Fig. 3 shows a further modified arrangement according to the invention. The difference between this arrangement and that shown in Fig. 2 is the fact that the band-pass filters are for different frequency ranges. Band-pass filter BP_1 allows the carrier frequency and all upper side band frequencies up to the n th component to pass, that is $f_0 + \Sigma n f_1$. Band-pass filter BP_2 only allows the frequency $f_0 - mf_1$ to pass. After passing the modulator M and the low-pass filter TP, a spectrum of successive oscillations $\Sigma(m+n)f_1$ is obtained.

Fig. 4 shows an arrangement which prevents the amplitudes of individual components in the spectrum from disappearing. It is based on the fundamental arrangement shown in Fig. 1. At the output end of the low-pass filter TP, where the fundamental frequency f_1 and the spectrum of its harmonics are present, provision is made to feed back or return a portion of the output over a band filter BP_3 and a frequency multiplier V to the reactance control element R. If a harmonic, for instance the p th harmonic, is very weak or not even present, the fundamental frequency f_1 is multiplied p -times in the multiplier. The current or voltage of frequency $p f_1$ which is thus obtained, is then applied to the reactance control R of the generator G together with the current of fundamental frequency f_1 . The side bands $f_0 \pm p f_1$ which were missing from the original spectrum are now present in the spectrum of the frequency-modulated oscillation of generator G. Further harmonics are also formed which may cause a desired amplification of further weak harmonics. The additional multiplier V may be omitted, this depending upon the amplitude distribution of the frequency spectrum.

Two practical applications of the method according to the invention are now described. Fig. 5 shows an arrangement for dividing a given frequency. The input energy of frequency

$$(m+n \pm 1)f_1$$

which is to be reduced to the frequency f_1 , is applied to the amplitude modulator M₁. In the latter it is superposed upon energy of auxiliary frequency $(m+n)f_1$, so that at the output end the frequency f_1 appears.

The auxiliary frequency $(m+n)f_1$ is derived from the output by using the device according to the invention. The procedure is as follows: The output frequency f_1 is passed to the reactance control element R and frequency modulates generator G having an average or center frequency f_0 . The generator voltage is passed to the band-pass filters BP_1 and BP_2 . Filter BP_1 allows frequency $f_0 + nf_1$ and filter BP_2 allows the frequency $f_0 - mf_1$ to pass and suppresses all the other

7 frequencies, including also the carrier frequency f_0 . Both frequencies reach the amplitude modulator M. The resulting difference frequency $(m+n)f_1$ is passed over the band-pass filter BP to the modulator M₁ already referred to. The entire system is a feed-back system capable of oscillating; stable conditions occur, however, if the frequency is divided in the ratio $1/m+n+1$.

10 The device according to the invention may also be used for the frequency multiplication of phase-modulated signals. Such an arrangement is shown in Fig. 6. V indicates the frequency multiplier which has already been described, with the difference that the frequency f_1 of the input signal applied to the reactance control R is already phase-modulated. The average or center frequency is f_g and is produced by generator G₁. By means of phase modulator PM frequency f_g is phase-modulated by the signal S which is to be transmitted; f_1 is then the phase-modulated frequency applied to the input end of the frequency multiplying device. The multiplication produces an average frequency $(m+n)f_g$ multiplied by the factor $(m+n)$, while at the same time the frequency deviation or variation limits are multiplied by the same factor.

15 After having explained the principle on which the device according to the invention operates, a few examples of more detailed diagrams of connections required for the individual basic arrangements are given. Figs. 7, 8, 9 show detailed diagrams corresponding, respectively, to the basic arrangements illustrated in Figs. 1, 2 and 4. Corresponding diagrams for the arrangements of 20 Figs. 3, 5 and 6 may be obtained by an analogous combination of the elements R, G, BP, M and TP. The reactance control element R shown is of the known type comprising a multi-grid electron tube. A condenser is connected between the 25 anode and the control grid. The input voltage with a frequency f_1 shifts the control grid voltage, whereby corresponding frequency alterations occur in the tube generator G in a manner well known to those skilled in the art. The subsequent band-pass filters BP, BP_1 as well as the low-pass filter TP are wave filters constructed in a known manner. Modulator M is of the type comprising two diodes which produce the demodulated voltage across a condenser-resistance load circuit. In Fig. 9, a frequency multiplier is shown. This contains a very powerful amplifier tube with non-linear characteristic and an anode circuit tuned to a harmonic of the frequency f_1 .

30 I claim:

1. A method of producing harmonics from a fundamental frequency comprising the steps of subjecting an auxiliary carrier frequency to a frequency modulation process in accordance with said fundamental frequency and mutually inter-modulating at least two side band frequencies obtained from said modulation process.

2. A method of producing harmonics from a fundamental frequency comprising the steps of frequency modulating an auxiliary carrier frequency in accordance with said fundamental frequency to produce a plurality of adjacent side band frequencies differing from each other by said fundamental frequency, and mutually inter-modulating at least two of said side band frequencies to produce a harmonic of said fundamental frequency.

3. A method of producing harmonics from a fundamental frequency comprising the steps of frequency modulating an auxiliary carrier frequency in accordance with the fundamental fre-

quency, the frequency deviation from said carrier frequency being a relatively large multiple of said fundamental frequency, segregating a predetermined band of side band frequencies from the modulation product, and mutually intermodulating said side band frequencies:

4. A method of producing harmonics from a fundamental frequency comprising the steps of frequency modulating an auxiliary carrier frequency in accordance with said fundamental frequency, the frequency deviation from said carrier frequency being a relatively large multiple of said fundamental frequency, segregating a predetermined band of side band frequencies from the modulation product, mutually intermodulating said side band frequencies to produce a spectrum of harmonics of said fundamental frequencies, and selecting a desired harmonic from said spectrum:

5. A system for producing harmonics from a fundamental frequency comprising an auxiliary oscillator having a frequency substantially higher than the highest harmonic of said fundamental frequency to be produced, frequency modulating means for modulating said oscillator in accordance with said fundamental frequency to produce a plurality of different order modulation side band frequencies progressively spaced from each other by intervals equal to said fundamental frequency, and means for deriving and mutually intermodulating at least two of the side band frequencies of said oscillator to produce a difference frequency corresponding to the desired harmonic of said fundamental frequency.

6. A system for producing harmonics from a fundamental frequency comprising an auxiliary oscillator having a frequency substantially higher than the highest harmonic frequency to be produced, frequency modulating means for modulating said oscillator in accordance with said fundamental frequency to produce a plurality of different order side band frequencies progressively spaced from each other by intervals equal to said fundamental frequency, means for deriving a plurality of side band frequencies from said oscillator, further means for mutually intermodulating the derived side band frequencies, and means for selecting the desired harmonic from the resultant modulation product.

7. A system for producing harmonics from a fundamental frequency comprising an auxiliary oscillator, means for frequency modulating said oscillator in accordance with said fundamental frequency, the frequency deviation from the normal oscillating frequency being relatively large compared with said fundamental frequency to produce a plurality of different order modulation side band frequencies progressively spaced from each other by said fundamental frequency, band-pass filter means connected to said oscillator, and means connected to the output of said filter means for mutually intermodulating the side band frequencies selected by said filter means.

8. A system for producing harmonics from a fundamental frequency comprising an auxiliary oscillator, frequency modulating means for modulating said oscillator in accordance with said fundamental frequency, the frequency deviation from the normal oscillating frequency being relatively large compared with said fundamental frequency to produce a plurality of different order modulation side band frequencies progressively spaced from each other by said fundamental frequency, band-pass filter means connected to said oscillator for selecting therefrom a plurality of

said side band frequencies, means for mutually intermodulating the side band frequencies selected by said band-pass filter means, and a low-pass filter having a limiting frequency equal to the passing range of said band-pass filter and connected to the output of said modulator:

9. A system for producing harmonics from a fundamental frequency of value f comprising an auxiliary oscillator producing a normal frequency of value f_0 , means for frequency modulating said oscillator in accordance with said fundamental frequency, the frequency deviation from said normal frequency being relatively large compared with said fundamental frequency to produce a plurality of different order modulation side band frequencies progressively spaced from each other by said fundamental frequency, a pair of band-pass filters connected to said oscillator and having frequency passing ranges $f_0 + mf$ and $f_0 - nf$, respectively, wherein m and n are whole numbers, and an amplitude modulator connected to both said band-pass filters for mutually intermodulating the side band frequencies selected by said filters and to produce harmonic combination frequencies of frequency $(m+n)f$:

10. A system for producing harmonics from a fundamental frequency of value f comprising an auxiliary oscillator producing a normal frequency of value f_0 , means for frequency modulating said oscillator in accordance with said fundamental frequency, the frequency deviation from said normal frequency being relatively large compared with said fundamental frequency to produce a plurality of different order modulation side band frequencies progressively spaced from each other by said fundamental frequency, a pair of band-pass filters connected to said oscillator and having frequency passing ranges $f_0 + mf$ and $f_0 - nf$, respectively, wherein m and n are whole numbers, an amplitude modulator connected to both said band-pass filters for mutually intermodulating the side band frequencies selected by said filters and to produce harmonic combination frequencies of frequency $(m+n)f$, and a low-pass filter connected to the output of said modulator having a limit frequency equal to $(m+n)f$.

11. A system for producing harmonics from a fundamental frequency comprising an auxiliary oscillator having a frequency substantially higher than the highest harmonic of said fundamental frequency to be produced, frequency modulating means for modulating said oscillator in accordance with said fundamental frequency to produce a plurality of different order modulation side band frequencies progressively spaced from each other by intervals equal to said fundamental frequency, and a band-pass filter having a passing range to encompass a pair of said side band frequencies spaced by a frequency interval equal to a desired harmonic of said fundamental, and means for mutually intermodulating the side band frequencies selected by said filter and for selecting the difference frequency from the resultant modulation product.

12. A system for producing harmonics from a fundamental frequency comprising an auxiliary oscillator having a frequency substantially higher than the highest harmonic of said fundamental frequency to be produced, frequency modulating means for modulating said oscillator in accordance with said fundamental frequency to produce a plurality of different order modulation side band frequencies progressively spaced from each other by intervals equal to said fundamental frequency, and a band-pass filter connected to said

oscillator and having a passing range to encompass a plurality of desired side band frequencies mutually spaced from each other by intervals equal to a plurality of harmonic frequencies of said fundamental frequency, and means for mutually intermodulating the side band frequencies selected by said filter and for selecting a desired difference frequency from the resultant modulation product.

13. A system for producing harmonics from a fundamental frequency of value f comprising an auxiliary oscillator having a normal frequency of value f_0 substantially higher than said fundamental frequency, means for frequency modulating said oscillator in accordance with said fundamental frequency, the frequency deviation from said normal frequency being relatively large compared with said fundamental frequency to produce a plurality of different order modulation side band frequencies progressively spaced from each other by a frequency range equal to said fundamental frequency, a pair of band-pass filters connected to said oscillator having frequency passing ranges $f_0 + \Sigma n f$ and $f_0 - m f$, respectively, wherein m and n are whole numbers, and amplitude modulating means connected to both said filters for mutually intermodulating the side band frequencies selected by said filters and to produce harmonic components of frequency $\Sigma(m+n)f$.

14. A system for producing harmonics from a fundamental frequency of value f comprising an auxiliary oscillator producing a normal frequency of value f_0 substantially higher than said fundamental frequency, means for frequency modulat-
